Des. 202,877
Patented Nov. 16, 1965

202,877

DOOR KNOCKER

John B. Morse, Hamden, and Fritz C. Benson, Shelton,
Conn., assignors to The H. B. Ives Company, New
Haven, Conn.

Filed Jan. 6, 1965, Ser. No. 83,296

Term of patent 14 years

(Cl. D10—7)

Fig. 1

Fig. 2

Fig. 5

Fig. 3***Fig. 4***

FIG. 1 is a front face view of a door knocker embodying our invention with the bail of the knocker being shown in raised position;

FIG. 2 is a similar view illustrating the knocker assembly with the bail in lowered position;

FIG. 3 is a perspective view of the knocker; and

FIG. 4 is a further perspective view of the knocker; and

FIG. 5 is a side elevational view of the knocker with the bail in raised position.

We claim:

The ornamental design for a door knocker, substantially as shown and described.
